BRASSIERE

Raymond C. Cole, Dover, Del., assignor to International Latex Corporation, Dover, Del., a corporation of Delaware

Filed Mar. 23, 1960, Ser. No. 59,849

Term of patent 14 years

(Cl. D20—4)

FIG. 1.

The front of the brassiere is conventional in appearance. The essential features of my design reside in the full line disclosure on the drawing.

I claim:

The ornamental design for a brassiere, substantially as shown and described.
